ATTORNEY

UNITED STATES PATENT OFFICE.

FREDERICK BAHMANN, OF BROOKLYN, NEW YORK.

FEVER-THERMOMETER.

SPECIFICATION forming part of Letters Patent No. 244,105, dated July 12, 1881.

Application filed April 14, 1881. (Model.)

To all whom it may concern:

Be it known that I, FREDERICK BAHMANN, of Brooklyn, in the county of Kings and State of New York, have invented certain new and 5 useful Improvements in Fever-Thermometers, of which the following is a specification.

The self-registering fever-thermometers heretofore in use were either made simply of a graduated tube above the mercury-bulb, in which 10 the indexing-column is separated by a small air-space, or by drawing out the end of the mercury-bulb into a thin tube and bending the same above the bulb into a flat S or loop shaped portion, which latter serves to retain 15 the indexing-column of mercury and to prevent the return of the same into the bulb. The thin drawn-out glass tube is protected by an exterior tube soldered to the mercury-bulb. Within the protecting-tube is arranged, back 20 of the mercury-column, a scale of opaque glass, which is securely connected to the exterior protecting-tube at the upper end. The objection to these well-known forms of thermometers was, that in the former case the indexing-column 25 of mercury was liable to return into the bulb, so as to defeat the very object of the thermometer, while the second thermometer was too complicated, requiring too many pieces.

The object of my invention is to furnish a 30 fever-thermometer in which the advantages of both thermometers heretofore described are combined—to wit, simplicity of construction and a reliable self-registering of the indexing mercury-column without any liability of its returning into the mercury-bulb; and the invention 35 consists of a fever-thermometer having a graduated upper tube, with a fine center-hole extending through the entire length of the same and sealed at the top, said tube being 40 drawn out at the lower end and bent into a flat S or loop shape, and connected to a second protecting-tube, which contains in its lower part the mercury-bulb, and which is connected to the main tube above the finely-drawn-out 45 loop-shaped portion.

In the accompanying drawings, Figure 1 represents a front view, and Fig. 2 an enlarged vertical central section, of the lower portion of my improved fever-thermometer. 50 Similar letters of reference indicate corresponding parts.

A in the drawings represents the upper or main part of my improved fever-thermometer, which consists of a graduated glass tube having a thin central perforation, within which 55 moves the indexing-column of mercury. The upper end of the main tube A is sealed, while the lower end is drawn out into a fine tube, B, and jointed to the mercury-bulb C' of a second glass tube, C. Before the drawn-out lower 60 part of the main tube A is jointed to the mercury-bulb of the tube C it is bent into the shape of a flat S or a flat loop, a, as shown in the drawings, which has the well-known effect of preventing the return of the indexing-column 65 of mercury into the bulb of the lower protecting-tube, C. The upper part of the protecting-tube C is sealed onto the lower part of the main tube A above the point where the same is drawn out, so as to inclose the looped or S-shaped 70 portion and prevent its breakage. The lower protecting-tube, C, and the bulb C' form, with the main tube A, a thermometer of uniform diameter throughout, which is fully protected, not liable to breakage, and which preserves in an accurate and reliable manner the 75 temperature indicated by the highest position of the indexing-column, owing to the fact that the same cannot return into the bulb, but is always reliably kept above the same. 80

Having thus described my invention, I claim as new and desire to secure by Letters Patent—

A self-registering fever-thermometer constructed of a graduated main tube closed at 85 the top and provided at the lower part with a drawn-out and bent or looped portion, and of a protecting-tube sealed to the main tube above the drawn-out portion, and provided with a mercury-bulb at the lower part, which latter 90 is sealed to the lower end of the drawn-out portion of the main tube, substantially as and for the purpose set forth.

In testimony that I claim the foregoing as my invention I have signed my name, in presence of two witnesses, this 9th day of April, 1881. 95

FREDERICK BAHMANN.
